UNITED STATES PATENT OFFICE.

LUNA J. ADERHOLD, OF WEDOWEE, ALABAMA.

IMPROVEMENT IN HOES.

Specification forming part of Letters Patent No. 105,405, dated July 19, 1870.

To all whom it may concern:

Be it known that I, LUNA J. ADERHOLD, of Wedowee, in the county of Randolph, and in the State of Alabama, have invented certain new and useful Improvements in Hoes; and do hereby declare that the following is a full, clear, and exact description thereof, reference being had to the accompanying drawing, and to the letters of reference marked thereon, making a part of this specification.

The nature of my invention consists in the construction and arrangement of a hoe for cultivating corn and cotton, and for other purposes.

In order to enable others skilled in the art to which my invention appertains to make and use the same, I will now proceed to describe its construction and operation, referring to the annexed drawing, in which—

Figure 1 is a side view, part in section, and Fig. 2 is a front view, of my hoe. Figs. 3 and 4 are views of blades to be substituted, when necessary, for the one represented in Figs. 1 and 2.

A represents the handle of my hoe, provided with a metal bar, a, on the upper, and another, b, on the lower side, and also with a metal band, d, surrounding the front end, the bars a and b extending back from the front end a suitable distance.

Near the front end of the beam A there is an elongated slot through the beam and bars a b, as shown by dotted lines in Fig. 1.

On the under side of the handle A is placed a metal bar, B, provided at its rear end on the upper side with a lug, e, which fits into notches made in the bar b, and is held by a metal strap, f, surrounding the beam A.

At the front end of the bar B is a screw-rod, g, which extends upward through the slot in the beam A, and is fastened by a nut, h, on top of the same.

The front end of said bar is extended downward a suitable distance, as shown in Fig. 1, and its lower end is bent forward and provided with a head, i. It will be noticed that immediately back of the head i the upper side of the forward-bent portion is inclined or beveled, for a purpose that will be presently described.

The front end of the bar b, on the under side

of the beam, is extended on both sides of the beam, and then bent downward, forming ears k k, which have a notch or recess cut in their lower edges, as shown.

C represents the hoe-blade, which is of square or rectangular form, with four cutting-edges, and in the center it has a slot, m, in the shape of a cross, as shown in Fig. 2. The ends of this slot are slightly beveled, but the sides are cut square.

D represents a shield or plate laid on the front side of the blade C, and having its upper end bent so as to fit over the top edge of the blade. In the body of the shield is a longitudinal slot, the sides of which are beveled inward, as shown in Fig. 2, and the upper end enlarged, so that the head i can pass through the same.

The head i of the bar B is passed through the cross-slot m of the blade C, and through the slot in the shield D, and the upper end of the shield placed over the top edge of the blade. The shield and blade are then placed against or in the notches or recesses in the ears k k, when, by tightening the screw-nut h, the blade is firmly secured. The head i, bearing against the beveled sides of the notch in the shield D, presses the blade C upon the incline or bevel in rear of the head i, which bevel, corresponding with the bevel at the end of the slot m, so to say, wedges the blade tightly.

The strap f is tightened by a wedge, E, inserted on the upper side of the beam A, said wedge having, at its outer end, jaws n n, forming a wrench for loosening or tightening the nut h.

By changing the bar B back or forth, so that the lug e will enter different holes in the bar b, the blade C may be set in any angle desired.

In place of the blade C, I may substitute the implements G and H, constructed as shown in Figs. 3 and 4.

G is a combined garden-hoe and plow, and H is a hoe to cut sprouts and shrubbery, both having a longitudinal slot, with an enlargement in the center.

Having thus fully described my invention, what I claim as new, and desire to secure by Letters Patent, is—

1. The bar B, constructed as described, and

provided with lug *e*, screw-rod *g*, and head *i*, with an incline or bevel immediately in rear of said head, and used with a hoe-handle and hoe, all substantially as and for the purposes herein set forth.

2. A four-edged hoe-blade provided with a central crucial slot, as shown and described.

3. The arrangement of the beam *A*, bar *B*, blade *C*, shield *D*, band *f*, and wedge *E*, all

constructed as described, to operate substantially as and for the purposes herein set forth.

In testimony that I claim the foregoing I have hereunto set my hand this 21st day of June, 1870.

LUNA J. ADERHOLD.
